UNITED STATES PATENT OFFICE.

CARLO TOMMASI, JOHN SANDHOLM, HEINRICH DANNEEL, AND AUGUSTO BUSCH, OF BASEL, SWITZERLAND, ASSIGNORS TO ELEKTRIZITÄTSWERK LONZA, OF BASEL, SWITZERLAND.

BURNER FOR SOLID FUEL.

Application filed February 20, 1922. Serial No. 538,041.

To all whom it may concern:

Be it known that we, CARLO TOMMASI, a subject of the King of Italy, JOHN SANDHOLM, a citizen of the Republic of Finland, **5** HEINRICH DANNEEL, a citizen of the German Republic, and AUGUSTO BUSCH, a subject of the King of Italy, all four residents of Basel, Switzerland, have invented a new and useful Burner for Solid Fuel, of which the **10** following is a full, clear, and exact specification.

This invention relates to all means for burning a solid fuel, such as the metaldehyde fuel described in our application filed **15** March 22, 1920, Serial No. 367,701, Patent #1,407,101 in such manner that the lowering of the surface where combustion takes place by gradual consumption of the fuel is automatically compensated for. Heretofore, in the use of solid fuels, such as solid **20** alcohol, as the burning proceeds the source of propagation of the flame becomes further and further removed from the object to be heated. The burner of the present invention, **25** is more particularly adapted for utilizing blocks or tablets of solid fuel in such manner that the block is progressively advanced as the heating continues and the surface of the block is burned off. Therefore, the **30** distance of the burning surface from the object to be heated will always be the same no matter how much of the block may have been consumed. It thus becomes possible to utilize every particle of the block without **35** waste, and to heat just as efficiently when the block has largely been consumed as when a new block is in place in the apparatus. Means are also provided for regulating the **40** area of the combustion surface of the fuel block, so that the volume of the flame may be increased or decreased at will. Further objects of the invention will hereinafter appear.

The invention will be understood by reference to the accompanying drawing in which,

Fig. 1 is a perspective view, partly in section, of a burner which is designed to hold an object in position to receive the flame.

Fig. 2 is a cross section in line 2—2, Fig. 1.

Fig. 3 is a sectional elevation of a burner

adapted for use as a pocket light, or for heating small objects, and

Fig. 4 is a cross section on line 4—4, **55** Fig. 3.

By reference to Figures 1 and 2, it will be seen that the embodiment of the invention therein shown comprises a base member **1**, preferably of metal, which is formed with **60** a centrally disposed rectangular chamber **2**, and a surrounding closed chamber **3**, which may be employed for the reception of a cooling fluid. Fitted within rectangular chamber **2**, for vertical movement therein, **65** is a table **4**, and disposed beneath the same is a spring **5** which tends to move the table upwardly. By the action of the said spring a fuel block **5** supported by the table is constantly maintained in such position that **70** its upper surface is engaged by a stop member **6**.

Stop member **6** is adjustable so as to cooperate with the table **4** and spring **5** to regulate the surface of combustion of **75** the fuel block, and hence the volume of the flame. In this connection it will be understood that when the fuel block is moved upwardly so that its sides are exposed for a certain distance above chamber **2**, the combustible surface of the block will be correspondingly augmented, because the flame will spread from the top of the block to the sides thus exposed. In the present embodiment of the invention, stop member **6** **80** is attached to a stiff wire **7** which passes downwardly through a shallow vertical slot **a** formed in the wall of chamber **2** and thence through a tube **t** communicating with said slot and soldered about the same to **85** provide a water tight connection. The opposite end of the tube has a similar water tight connection with a slot **b** formed in the outer wall of the burner. Exterior to this slot the wire **7** is secured to a button **8**. **90**

Button **8** is movable in slot **b** so as to vary its distance from slot **a**, and hence it may be manipulated to adjust the position of contact member **6**. This construction permits the stop member to be moved downwardly into such position that the block of fuel on table **4** may be depressed so that its upper surface will lie flush with the top of chamber **2**. In such position the com-

bustible area of the block will be limited to its exposed upper surface. When, however, button 8 is moved to the left from its position as Fig. 1, stop member 6 will be correspondingly elevated, and, simultaneously, table 4 and the fuel block will be moved upwardly by the spring. This construction, in addition to providing means for increasing or decreasing the volume of flame, permits the stop member to be moved into such position that a new block of fuel may be conveniently inserted when desired.

The burner illustrated in Fig. 1, is provided with a cover 8* conforming with the upper surface of the burner proper, and at its outer end provided with a hinge-clasp 9, which may be swung in position to form a support for the outer end of the cover when the burner is in position for use, and which may be swung in position to engage the lower wall of a projection 10 when the cover is closed. In this form of burner the cover is designed to support a curling iron or the like, indicated in dotted lines, and for this purpose the cover is formed with a flange 8* which is cut away at 10 to form a semi-circular seat to receive the handle of the curling iron, and to act in conjunction with the opposite raised wall 11 to support the curling iron at two points. The base of the cover, in its open position, is adapted to hold an asbestos sheet 12, which will come into contact with the burning surface of the block when the cover is moved to closed position, thus extinguishing the flame.

As hereinbefore stated, chamber 3 may be employed for the reception of cooling fluid. In practice this cooling fluid may be water, inasmuch as the heat to which the burner is subjected is insufficient to raise the water to the steaming point. For this reason the water may be permanently sealed within the chamber if desired. In the construction of the burner, the base plate *p* may be soldered or welded to the side walls of the burner after the water is placed in the chamber, or the chamber may be provided with a suitable valve through which the cooling liquid may be admitted at any time.

In the form of the invention illustrated in Figures 3 and 4, the burner is adapted as a pocket light, or for heating small objects, such as surgical or dental instruments. To this end the height of the burner is substantially greater than its width, and it is formed with a central fuel chamber 13 which is adapted to contain a relatively long and narrow block of fuel 14. Disposed on opposite sides of fuel chamber 13 are enclosed chambers 15, which may serve for the reception of a cooling fluid, and these chambers may entirely surround the fuel chamber 13, if desired, the cooling fluid being

admitted through an inlet normally closed by screw 16.

Fitted within chamber 13 for vertical movement therein, is a table 17 upon which the fuel block 14 rests, and a spring 18 acts upon the table to move the fuel block upwardly into contact with a stop member 19 of any suitable form. In the present instance the stop member 19 consists of a wire inwardly and rectangularly bent at its upper end, and leading downwardly intermediate chamber 13 and an outer wall of the burner, its lower end being secured to button 21 working in a plate 20 and in register with a depression 20* formed in the outer wall of the burner. A vertical slot is formed in depression 20, for the passage of the stem of the button 21 which is thereby secured to plate 20. By moving the button vertically stop member 19 may be adjusted so as to regulate the combustion area of the fuel block, and the volume of the flame, as described with respect to the construction shown in the preceding figures.

It will be understood that in either embodiment the supporting table for the fuel block may be manually elevated by any suitable means, the spring being dispensed with. For example, as shown in Fig. 4, the table may be connected to the stem 22 of a button 22* disposed exterior to a vertical slot 23 formed in the outer wall of the burner so that the table may be periodically elevated by means of the button as the burning of the fuel block progresses. In said case, the friction between the table and the walls of the fuel chamber will serve to hold the table in the position to which it is moved, or the button may be threaded on stem 22, so that it may be turned to clamp the table in its adjusted position, as shown in Fig. 4.

Having described my invention, what I claim and desire to secure by Letters Patent is:

1. A burner comprising means for supporting a block of fuel; a stop; means for urging the fuel block towards the stop; and means for varying the position of the stop.
2. A burner provided with means for supporting a block of fuel; means providing a recess having walls adapted to contain said block of fuel; a stop; means for urging a block of fuel towards the stop; and means for elevating or depressing the stop whereby to depress or lower the block of fuel above or below the walls of said recess.
3. A burner provided with means for supporting a block of fuel; means for feeding said fuel in proportion as it is consumed; and means for regulating the rate of consumption of said fuel.
4. A burner comprising means forming a chamber for a body of fuel; a support for the

fuel; means for elevating said support; a stop carried by the burner and adapted to engage the body of fuel; and means for adjusting the position of the stop.

5 5. A burner comprising in combination means for supporting a block of fuel exposing a portion thereof to the atmosphere for combustion along the exposed portion; and means carried by the burner for varying 10 the extent of exposure of said block.

In witness whereof we have hereunto

signed our names this 14th day of January, 1922, in the presence of two subscribing witnesses.

CARLO TOMMASI,
JOHN SANDHOLM,
HEINRICH DANNEEL,
AUGUSTO BUSCH.
